UNITED STATES PATENT OFFICE.

FRANK A. HENDRICKSON AND MATT LUOMA, OF GREAT FALLS, MONTANA.

ATTACHMENT FOR PNEUMATIC DRILLS.

Application filed May 4, 1923. Serial No. 636,644.

The object of this invention is to provide means for conveying the exhaust air from a pneumatic drill, to a point of discharge, in order that the workman handling the drill 5 may not be obliged to breathe the dust usually stirred up by the exhaust air, which frequently results in serious affections of the throat or lungs.

A further object is to provide an attachment including a plurality of tubes so positioned that one tube will convey the air from each exhaust port and conduct it to a main pipe and thence to an air hose, whereby the expanded air may be conducted to a suitable 15 point of discharge.

A still further object is to provide for readily connecting the attachment to a drill casing.

With the foregoing and other objects in view, the invention consists in the novel construction, combination and arrangement of elements described, illustrated and claimed, it being understood that modifications may be made within the scope of the claim without departing from the spirit of the invention. 25

In the drawings, Figure 1 shows the device in elevation, as applied to the casing of a pneumatic drill; Figure 2 is an elevation 30 from another angle, of the rigid pipe connection for use between the casing and the flexible discharge pipe; Figure 3 is a plan view of the construction of Figure 2; Figure 4 is a perspective view of a securing device, 35 for mounting the attachment; Figure 5 is an elevation with parts in section, showing a slight modification, in which detachable connections for the branch pipes are provided.

The casing of a drill is designated 10 and 40 exhaust ports 11 serve the usual purpose, the ports being differently spaced on drills of different makes, so that a special attachment will be required for each standard make of drill.

45 Communicating with the ports 11 are short pipes or tubes 12, which in turn have communication with longer tubes 13 preferably curved or deflected as shown, in order to fit the drill casing.

A main tube 14 is of sufficient size to carry 50 the volume of air issuing from all of the ports and discharged through the other tubes just referred to, tube 14 having a threaded end 15 with which an air hose may be connected, so that the exhaust air may be 55 discharged at a suitable distance from the point where the work is being carried on.

It will be observed from the drawing that the elements 12 and 13 constituting branch pipes, are offset with reference to the main 60 tube 14, and form a plurality of pairs of ducts projecting in the direction necessary for establishing communication with the ports of a standard casing, when the main pipe is parallel with the longitudinal axis 65 of the casing.

A bracket 16 may comprise two resilient arms and a central portion 17 passing around the tube 14 and secured thereto. The approaching ends of the arms are provided 70 with engaging devices 18 and 19, permitting the bracket to be secured to the drill casing.

In one form of the device threaded pipe unions 20 serve to connect the individual pipes with the casing, complementary 75 threaded elements 21 being welded to the casing, in registration with the exhaust ports.

What is claimed is:

An exhaust attachment for a pneumatic 80 drill, including a casing and exhaust ports, said attachment comprising a rigid main pipe, rigid branch pipes offset with reference to the main pipe and forming a plurality of pairs of ducts on each side of the main pipe 85 for establishing communication with the ports, when the main pipe is disposed in parallel relation with the longitudinal axis of the casing, and a bracket proportioned to mount the main pipe on the casing in the 90 aforesaid relation to the longitudinal axis of the casing, with the branch pipes in alignment with the ports.

In testimony whereof we affix our signatures.

FRANK A. HENDRICKSON.
MATT LUOMA.
